DRILL BIT

Clarence H. Black, Houston, Tex., assignor to
Reed Roller Bit Company, Houston, Tex., a corporation of Texas.

Application October 12, 1939, Serial No. 299,088

4 Claims. (Cl. 255—71)

This invention pertains to drill bits, and more particularly to those in which cross-cutters are mounted on a transverse shaft at the forward end of the bit.

5 In bits of this type it is obvious that strength and rigidity of the roller shaft are of prime importance, and such qualities are best achieved by making the shaft integral with the depending legs which support it. This construction, however, creates the problem of joinder between two sections of shaft, since the shaft must be made in two pieces to permit the rollers to be placed thereon. Various types of joints have been utilized for this purpose, but, so far as I am aware, no one 10 has developed a joint in a structure of this kind embodying the features of my invention, by which firm rigidity and durability in the cross cutter shaft are attained.

The object of this invention is to increase the 20 strength and durability of cross cutter shafts in drill bits.

This and other objects I accomplish by my invention, one specific example of which is shown in the accompanying drawing and fully described 25 hereinafter.

Further objects and features will become evident from the following disclosure when taken in connection with the accompanying drawing, in which:

30 Fig. 1 is a side elevation, partly in cross-section, of a drill bit utilizing my invention, and

Fig. 2 is a cross-section taken along the line 2—2 of Fig. 1.

Referring to the drawing in detail, a drill bit 35 head 11 has, welded thereto, depending legs 12, 12'. Made integral with these legs are sections 13, 13' of the cross cutter shaft, and the ends of these sections are formed with interlocking projections 14, 14' (see Fig. 2) which coat as shown 40 to produce a smooth cylindrical joint. Formed in the abutting sides of these projections are tapered channels 15, 15' which form therebetween a tapered hole of circular cross-section transversely through the shaft.

45 Cutters 16, 16' are rotatably mounted on the shaft sections 13, 13' and are separated by a bridge 17 which extends between the usual side cutters 17' and has an aperture therein embracing the shaft at its place of joinder. This bridge 50 has an aperture 18 and a socket 19 which are adapted to register with the top and bottom of the hole 15, 15' respectively, and a tapered pin 20 is fitted through the aperture 18 and the hole 15, 15' and into the socket 19. The pin is welded 55 in the aperture 18 as shown at 21 to produce a

firm, unbreakable joint between the shaft sections.

In assembling, one of the cutters, such as 16, is placed on its shaft section 13 and the bridge 17 is fitted in place. The other shaft section 13', 5 upon which the cutter 16' has previously been placed, is then fitted into the collar so that the projections 14 and 14' fit together and the pin 20 is pushed into the hole 15, 15' and welded 10 therein, and the legs 12, 12' are welded in place 10 on the bit head 11. By these means I produce a bit with a firm and rigid cross cutter shaft.

Although a preferred embodiment of my invention is described above, I do not wish to be limited thereto, but only by the scope of the appended claims.

I claim:

1. In a drill bit, depending legs, a shaft section carried by each leg, roller cutters mounted on the shaft sections, and a joinder structure for the sections comprising coacting overlapping projections on the sections which fit together to form a cylindrical surface, oppositely disposed coacting channels in the abutting surfaces of the sections forming a transverse hole partly in each shaft section, a pin in the hole to hold the two sections together, and a member having an opening therein embracing the projections to prevent them from separating laterally.

2. In a drill bit, depending legs, a shaft section carried by each leg, roller cutters mounted on the shaft sections, and a joinder structure for the sections comprising coacting overlapping semi-cylindrical projections, oppositely disposed coacting channels in the abutting flat surfaces of the projections forming a transverse hole partly in each shaft section, a pin in the hole to hold the two sections together, and a member having an opening therein embracing the projections to prevent them from separating laterally.

3. In a drill bit, depending legs, a shaft section carried by each leg, roller cutters mounted on the shaft sections, and a joinder structure for the sections comprising coacting overlapping projections semi-circular in cross-section, oppositely disposed coacting channels in the abutting flat surfaces of the projections forming a transverse hole partly in each shaft section, a member having an opening therein embracing the projections, apertures in said member adapted to register with the ends of the hole, and a pin inserted in the apertures and through the hole to hold the two sections together.

4. In a drill bit, depending legs, a shaft section made integral with each leg, roller cutters mount-

ed on the shaft sections, and a joinder structure for the sections comprising coacting overlapping projections semi-circular in cross-section, oppositely disposed coacting channels in the abutting flat surfaces of the projections forming a transverse tapered hole, circular in cross-section, partly in each shaft section, a member having an opening therein embracing the projections, aper-

tures in said member adapted to register with the ends of the hole, a pin welded in the apertures and extending through the hole to hold the two sections together, said member being of a width to space said roller cutters so that they rotate between the legs and the member. 5

CLARENCE H. BLACK.
